Inventor.

UNITED STATES PATENT OFFICE.

RUDOLPH M. HUNTER, OF PHILADELPHIA, PENNSYLVANIA.

DOLL.

SPECIFICATION forming part of Letters Patent No. 634,143, dated October 3, 1899.

Application filed February 10, 1899. Serial No. 705,149. (No model.)

To all whom it may concern:

Be it known that I, RUDOLPH M. HUNTER, of the city and county of Philadelphia, State of Pennsylvania, have invented an Improvement 5 in Dolls, of which the following is a specification.

My invention of this application (Case 306) has reference to dolls; and it consists of certain improvements which are fully set forth 10 in the following specification and shown in the accompanying drawings, which form a part thereof.

My invention has for its object to improve the realistic or life effect of a doll by imparting to the eyes when open a capacity for automatically turning the pupils laterally to one side or the other, as if the attention were suddenly attracted to the persons handling the doll or adjacent to it. The result of this is 15 to give a most lifelike and wide-awake effect and at the same time permit the well-known sleeping action to take place upon laying the doll down upon its back. In my preferred construction both of these results are enabled to 20 take place automatically under gravity-actuated devices; but it is to be understood that so far as my invention is concerned in its most generic sense the sleeping movement 25 may be omitted, if desired.

My invention will be better understood by reference to the drawings, in which—

Figure 1 is a front elevation of a doll's head, showing the eyes looking sidewise as in one of the adjustments. Fig. 2 is a side elevation of the doll's head with a portion of the porcelain head cut away to show the interior mechanism. Fig. 3 is a plan view of the same with the upper portion of the porcelain head cutaway. Fig. 4 is a perspective view of the 35 mechanism of the eyes removed from the head. Fig. 5 is a perspective view of a modification, showing eyelids independent of the eyeballs. Fig. 6 is a perspective view of a modified form of the eye mechanism, and Fig. 7 is a sectional elevation showing another modification directed to the eyelids and mode of pivoting the structure.

A is the porcelain head of any suitable construction or design. It has the eye holes or 40 sockets T, as is customary.

B is a horizontal rocking frame having end cup-pieces forming rounded or ball-shaped

bearings C, which may have central small pivot protuberances c to make disengagement less possible. This frame B is pivoted in the 55 head by the plaster sockets D and is provided with a downwardly-extending arm K, carrying a weight L to insure its normally hanging in a definite position. This weight may be arrested in one direction by a cork abutment M, cemented to the head, and in the other direction by an upwardly-extending arm I from the frame B coming in contact with another cork abutment arranged in the upper part of the head. The movement permitted is first sufficient to enable the eyelids 60 e to close the sockets T.

E E are the two eyeballs and are secured by cement or otherwise upon wires journaled at F in the rocking frame B, so that said eyeballs rotate about vertically on upright axes. These wires extend rearward in arms or levers G and are loosely pivoted to the weight H, so that the parts B H G act like a parallel ruler. If the doll is tilted slightly to one 70 side or the other, the weight H by gravity will move to that side and the pupils of the eyeballs will be moved in the other direction or laterally, so as to give the appearance of looking sidewise. The weight may 75 have its movement limited in any manner desired; but, as shown, I have put felt pads h on the ends to prevent sound when it strikes the side of the head. If desired, pads or cork abutments, such as M J, may be employed 80 for the weight H to strike against, as is self-evident. In the particular construction shown in Figs. 2, 3, and 4 I prefer that the weight L shall be heavy and weight H reasonably light, so as to make the lateral movements of the 85 eyes very sensitive and quick-acting, as this permits them to respond to the very slightest tilting of the head to the side.

If desired, the arms G may have separate weights, as at H', Fig. 3, so that the eyes are 90 wholly independent in their lateral movements. It will be observed that each of the eyeballs is independently movable about a vertical or upright axis, and yet they are both bodily carried by the frame B, and hence rock 95 upon the same transverse or horizontal axis as when closing the lids. In Figs. 2, 3, and 4 the upper portion of the eyeballs are painted and waxed to represent the eyelids c, and 100

hence when turned over the sockets the appearance of closing the eyes in sleep is secured just as perfectly as in the old constructions. It is evident, however, that it is not at all necessary to make the eyelids on the eyeballs or to move upon the vertical axes, as they may be made of thin sheet metal, as at *c* in Fig. 5, and movable with the rocking frame on its transverse axis, or they may be formed as in Fig. 7, to be later described. It is preferable to make the surface of the eyeballs perfectly spherical, so far as the front portions are concerned, and to make them fit singly without touching the cup-plates of the curved or ball-shaped bearings *C*, so that in their various movements no irregularity of action or binding will result. By employing bearings *C* of large area considerable friction is secured, so that the eyelids will not descend under ordinary movements of the doll when it is not intended to represent sleep, and this also insures more durability where the sockets *D* are of plaster.

I would point out that, if desired, the weight *H* may be made heavier and the weight *L* dispensed with, the arm *K* acting as a stop, since the weight *H* may be made to perform the dual function of moving the eyes both upon horizontal and vertical axes, said movements being ordinarily required at different times. If this is desired, it would be advisable to follow the construction shown in Fig. 6, so as to reduce as far as possible the friction and permit greater leverage, and hence more sensitive action, of the eyeballs for lateral movement of the pupils. In this construction the arms *I* and *K'* limit the rocking movements of the frame *B*, so as to hang down almost vertically. The arms *G* of the eyeballs are made short and are linked together and to the weighted arm *P* by link *R*. By this means a great leverage may be had on arm *P*, while a short leverage is employed on arm *G*, thus permitting a full movement of the eyes for a small lateral movement of the weighted arm.

In the modification shown in Fig. 7 each of the eyeballs *E* is supported within a thin clear glass envelop *E'*, covering the front part of the eye or pupil and secured to the rocking frame *B*. The upper portion of this envelop *E'* may be colored and waxed to form the stationary eyelids which move with the rocking frame. Of course it is evident that in this modification the sides of the glass envelops *E'* will act as the bearings *C* and be journaled in the plaster sockets *D*, as is ordinarily done. The lateral movements of the pupils will be seen through the clear glass envelops *E'*. While I prefer the constructions herein set out as excellently adapted to the purpose of my invention from a practical standpoint, nevertheless I do not limit myself to the details thereof, as they may be modified in various ways without departing from the spirit of my invention.

Having now described my invention, what I claim as new, and desire to secure by Letters Patent, is—

1. A doll's head combined with eyes pivoted upon independent vertical or upright axes and carried upon a common support movable upon a horizontal or transverse axis, and means for moving said eyes both upon the upright and horizontal axes. 70

2. A doll's head combined with eyes pivoted upon independent vertical or upright axes and carried upon a common support movable upon a horizontal or transverse axis, and gravity-actuated devices for moving the eyes about their upright axes and also upon their horizontal axes. 80

3. A doll's head combined with a frame supported within the head, eyes pivoted upon independent vertical or upright rods in said frame so that the pupils may move laterally in the sockets, and gravity-controlled devices supported by the frame for automatically causing said eyes to rotate or move upon the axes of said vertical or upright rods. 85

4. A doll's head combined with a metal frame supported within the head, eyes pivoted in said frame by means of vertical or upright axes so that the pupils may move laterally in the sockets, and gravity-controlled devices also directly supported by the frame and connecting with the vertical or upright axes of both eyeballs, the construction being such that all of the movable parts are carried by a common frame. 90

5. As a new article of manufacture a doll's head combined with universally-pivoted eyes, a common frame or support for the eyes independent of and movable within the head, and gravity-controlled devices for moving said eyes carried by and having their weight supported by the common frame. 105

6. The combination of a doll's head having eye-sockets, a rocking frame journaled in the head on a transverse axis, two independent eyes carried by said rocking frame and having capacity for moving their pupils laterally, and gravity-actuated means for rocking said frame and moving the eyes bodily on the transverse axis and also to cause the pupils thereof to move laterally in the sockets. 110

7. The combination of a doll's head having eye-sockets, a rocking frame journaled in the head on a transverse axis, two independent eyes carried by said rocking frame and having capacity for moving their pupils laterally, gravity-actuated means for rocking said frame and moving the eyes bodily on the transverse axis and also to cause the pupils thereof to move laterally in the sockets, and suitable eyelids movable over the eye-sockets in the head under the action of the rocking frame. 120

8. The combination of a doll's head having eye-sockets, a gravity-actuated rocking frame journaled in the head so as to be movable on a transverse axis, two independent eyeballs journaled upon the rocking frame on upright 130

axes, inwardly-extending arms or levers for rocking said eyeballs, and gravity-actuated means for moving said arms or levers.

9. The combination of a doll's head having 5 eye-sockets, a gravity-actuated rocking frame journaled in the head so as to be movable on a transverse axis, two independent eyeballs journaled upon the rocking frame on upright axes, inwardly-extending arms or levers for 10 rocking said eyeballs, connecting means between said arms or levers to make the eyes move in unison, and gravity-actuated means for moving said arms or levers.

10. A doll's head combined with eyeballs 15 universally movable within the eye-sockets of the head and supported upon a rocking frame pivoted within the head, and gravity-actuated devices for universally moving said eyeballs supported by said rocking frame.

11. A doll's head having laterally or side-20 wise movable pupils independently and respectively pivoted upon upright rods the axes of which substantially pass through the centers of curvature of the eyeballs said rods having rearward extensions or arms, combined 25 with gravity-actuated devices loosely connecting the rear ends of said arms for automatically moving said pupils.

12. A doll's head having eye-sockets, com-

bined with a rocking frame having at each 30 end outwardly-curved or ball-shaped pivots, two eyeballs pivoted to the rocking frame by upright bearings, bearings in the head for supporting the curved or ball-shaped pivots, and gravity-actuated devices having their 35 weight carried by the rocking frame for moving the frame and the eyeballs thereon on their upright bearings.

13. A doll's head having eye-sockets, com-40 bined with a rocking frame pivoted to the head, two eyeballs journaled upon the rocking frame upon upright axes, stops to limit the movement of the rocking frame, and gravity-actuated devices sustained by the rocking frame for moving it and also the eyeballs. 45

14. A frame structure for carrying eyeballs for a doll's head, consisting of a frame having downwardly-extending upright bearings F, F, for the eyeballs and upwardly and laterally extending end bearings C made rounded or 50 ball-shaped and having the central extensions c thereon.

In testimony of which invention I have hereunto set my hand.
